UNITED STATES PATENT OFFICE.

RICHMOND STILES DICKERSON, OF KISSIMMEE, FLORIDA.

BOTTLE.

SPECIFICATION forming part of Letters Patent No. 591,212, dated October 5, 1897.

Application filed April 6, 1896. Serial No. 586,363. (No model.)

To all whom it may concern:

Be it known that I, RICHMOND STILES DICKERSON, a citizen of the United States, and a resident of Kissimmee, in the county of Osceola and State of Florida, have invented certain new and useful Improvements in Bottles, of which the following is a specification, reference being had to the accompanying drawing, forming a part thereof, in which similar letters of reference indicate corresponding parts.

This invention relates to bottles, jugs, jars, and similar vessels; and the object thereof is to provide a vessel of this class which having been once filled and sealed may be emptied of its contents, but cannot be refilled or reused without leaving evidence of the fact.

The invention is fully disclosed in the following specification, of which the accompanying drawing forms a part, in which the figure clearly illustrates the invention.

In the practice of my invention I have shown a bottle A, provided with a neck B, and formed in the inner walls of the upper portion thereof 25 is an annular groove or enlargement L, and I also employ a tubular plug N, which is opened at the bottom and closed at the top, and the top thereof is provided with a ball or spherical body b², between which and the plug proper is a deep annular groove D, and the upper portion of the tubular plug N is also cut away to correspond with the annular groove or enlargement L in the neck B, and in sealing the bottle or vessel the cork H is first inserted into the bottom of the tubular plug, and said tubular plug is forced into the neck and the annular chamber formed by the annular groove or enlargement L in the neck B, and the correspondingly cut-away portion 40 of the tubular plug N is then filled with cement, as shown at k, said cement being placed

in said chamber while in a plastic condition, and after the same is set and becomes hard the tubular plug N cannot be removed, and the only way to empty the bottle is to break 45 off the ball or spherical body b², and this will be proof that the bottle has once been filled and emptied.

Instead of employing the annular chamber in which the plastic cement is placed for holding the tubular plug N in position within the neck, said plug may be secured in place in any desired manner.

In breaking off the ball or spherical body b² I employ a tool or instrument which is constructed in the manner of an ordinary pair of forceps and provided with jaws which exactly fit the part to be broken off.

Having fully described my invention, I claim as new and desire to secure by Letters 60 Patent—

The combination with a bottle or other vessel provided with a neck B and having formed in the inner walls of the upper portion thereof an annular groove or enlargement L of a tubular plug N which is opened at the bottom and closed at the top and provided with a spherical body b² between which and the plug is a deep annular groove D the upper portion of said plug N being cut away to correspond 65 with the enlargement L and the cork in the neck of the bottle inside of the plug and cement to secure the plug in the neck of the bottle.

In testimony that I claim the foregoing as 75 my invention I have signed my name, in presence of the subscribing witnesses, this 12th day of March, 1896.

RICHMOND STILES DICKERSON.
